UNITED STATES PATENT OFFICE.

WILLIAM MARTIN SIMMONS, OF HINTON, WEST VIRGINIA, ASSIGNOR OF ONE-THIRD TO
FRANK R. PUCKETT AND ONE-THIRD TO WILLIAM H. GARNETT, OF HINTON, WEST
VIRGINIA.

COMPOSITION OF MATTER TO BE USED IN PACKING JOURNALS OF RAILWAY-CARS.

No. 923,304.

Specification of Letters Patent.

Patented June 1, 1909.

Application filed July 11, 1907. Serial No. 383,316.

To all whom it may concern:

Be it known that I, WILLIAM MARTIN SIMMONS, a citizen of the United States, residing at Hinton, in the county of Summers and State of West Virginia, have invented a new and useful composition of matter to be used in packing journals of railway-cars, engines, and other journals where high speed is requisite and for thoroughly oiling and lubricating the same, of which the following is a specification.

Graphite _____ 50 pounds.
White lead ground in oil _____ 50 "
Clean grease _____ 37 "
15 Lye (any standard brand) _____ 9 "

These ingredients should be thoroughly mingled in the following manner: Take the required amount of grease or fat, place it in 20 a kettle and heat by a slow fire until it becomes of an oily consistency and then add the lye slowly, stirring all the time, gradually add the graphite and white lead in equal proportions until the entire composition is complete, stirring the mixture constantly for twenty minutes or half an hour.

In using the above named composition the journals or other parts of machinery on

which the same is to be used should be thoroughly cleansed, when the composition 30 can be applied as a paste, but for use in keeping the journals of railway cars and engines cool cotton waste should be dipped into the composition and the journals packed in the usual manner.

35

By the use of the above named composition all the parts of the machinery necessary to be lubricated are kept thoroughly saturated with oil and the parts are maintained at a low degree of temperature, and the 40 composition gives additional life to the machinery and materially lessens the expense and cost of keeping the same lubricated, and in suitable condition for service. Packing with the above composition is only required 45 once in several months.

I claim:

The herein - described product resulting from the mixture of graphite fifty pounds, white lead fifty pounds, clean grease thirty- 50 seven pounds, and lye nine pounds, substantially as described.

WILLIAM MARTIN SIMMONS.
